STUDIO COUCH

Joseph Martin, Laurelton, N. Y., assignor to
 United States Cabinet Bed Co., Brooklyn, N. Y.,
 a corporation of New York

Application December 18, 1934, Serial No. 758,015

15 Claims. (Cl. 5—18)

This invention relates to studio couches in general and more especially to a studio couch having an all metal studio couch bed frame.

Among the objects of the present invention, it is aimed to provide an improved all metal frame for the outer bed section of a studio couch, which frame defines the form of the outer bed section including its leg enclosures.

It is still another object of the present invention to provide an improved outer bed section 10 having a studio couch including an all metal frame and a fabric intimately engaging the outer faces of the all metal frame to form a smooth outer fabric finish.

It is still another object of the present invention to provide an improved means for fastening and tightening the fabric to the outer faces of the metal frame.

These and other features, capabilities and advantages of the invention will appear from the 20 subjoined detail description of one specific embodiment thereof illustrated in the accompanying drawings in which

Figure 1 is a perspective of a studio couch made according to the present invention;

25 Fig. 2 is a transverse section on the line 2—2 of Fig. 1 with the bed sections in single bed formation;

Fig. 3 is an end elevation partly in section on a smaller scale of the studio couch in double bed 30 formation;

Fig. 4 is a longitudinal vertical section on the line 4—4 of Fig. 5;

Fig. 5 is a longitudinal horizontal section on the line 5—5 of Fig. 4;

35 Fig. 6 is a fragmental plan view looking upwardly at one end of a portion of the frames;

Fig. 7 is a fragmental perspective partly in section showing part of the means for fastening and stiffening the fabric in position on the frame; 40 and

Fig. 8 is a fragmental perspective partly in section showing another part of the means for fastening and stiffening the fabric in position on the frame.

45 In the embodiment illustrated, there is shown a main inner bed section 1 which is housed underneath the movable bed section 2 in single bed formation, see Figs. 2 and 4 particularly.

50 The bed section 1 is characterized mainly by having an all metal frame composed of an angle iron longitudinally extending rear bar 3, a shorter angle iron longitudinally extending front bar 4, two angle iron laterally extending side bars 5 and 6 and two short angle iron bars 7 and 8 con-

nected the ends of the front bar 4 with the front ends of the side bars 5 and 6, four leg forming standards 9, 10, 11 and 12 composed of angle iron, and a flat wire bed spring 13 connected to the frame. The bars 4, 5, 6, 7 and 8 in the present instance are parts of an integral angle iron bar 5 bent into shape and notched at the bends.

The short angle iron portions 7 and 8 are inclined toward the end bars 5 and 6 from the front bar 4 in order to clear the rounded front corners of the movable bed section 2.

In the present instance, the flat wire bed spring 13 has its ends connected to the end bars 5 and 6 and to the short bars 7 and 8 and is otherwise not connected to the bars 3 and 4.

Furthermore, the leg forming standards 9 and 10 have one of their vertically extending webs secured as for instance by rivets to the downwardly extending web of the angle iron 3 and the standards 11 and 12 have one of their vertically extending webs secured as for instance by rivets to the downwardly extending webs of the angle irons 7 and 8.

To the lower ends of the standards 9, 10, 11 and 12, there are secured the upwardly extending wings 113 of the caps 14 having downwardly extending rounded extensions 15 to form smooth round floor engaging surfaces.

The movable bed section 2 has a channel iron bar 16 extending the full length of the bed section 30 and along the two ends of the bed section.

The altitude of the intermediate web 17 of the bar 16 in the present instance is substantially the thickness or depth of the built-in mattress 18 and has two horizontally extending web portions 19 and 20 extending inwardly.

The channel bar 16 is rounded at the front corners to form two end walls 21 and 22, a front wall 23 and two intermediate rounded corners 24 and 25. To the upper faces of the rear ends 40 of the web 19, there is secured preferably by rivets the horizontally extending web 26 of the angle iron bar 27 having its vertically extending web 28 extending upwardly from said web 26. The web 19 of the end walls 21 and 22 is connected by the longitudinally extending supporting wires 29 and the web 26 of the angle iron 27 is connected to the web 19 of the front wall 23 by the transversely extending supporting wires 30. The wires 29 and 30 cross one another as shown 50 in Fig. 5 and are connected to the lower ends of the coil bed springs 31. The upper ends of the coil bed springs 31 as shown are preferably connected to the lower face of the filled fabric portion 32 of the mattress 18.

This fabric portion 32 as shown preferably has a downwardly extending portion 33 extending down to the upper face of the web 19 of the wall 23 of the channel bar 16. The mattress 18 also 5 has downwardly extending side walls 34 and 35 and a downwardly extending rear wall 36, the lower edges of the walls 34 and 35 being spaced from the web 19 of the side walls 21 and 22 but the lower edge of the rear wall 36 extending down 10 to the upper edge of the web 28 as shown in Figs. 2 and 4.

In order to provide an ornamental finish in the interest of appearance, the outer faces of the front and side walls of the channel bar 16 and 15 mattress 18 and the outer faces of the rear wall of the mattress 18 and of the web 28 are enclosed or covered by the cover fabric 37 which consists essentially in a plane upper surface covering 38 cut to conform to the upper face of the mattress 18, an apron portion 39 to extend down along the side walls of the mattress 18 and channel bar 16, and a rear apron portion 40 to extend down along the rear wall of the mattress 18 and the rear face of the web 28.

25 The lower end of the apron portion 39 is provided with an inwardly extending flange portion 41 to extend around and into engagement with the lower face of the web 20 of the channel bar 16. The inner end of the flange portion 41 is 30 preferably folded back upon itself in the form of a hem to form a pocket at the inner end thereof for a reinforcement, such as a wire 42. The wire 42 is preferably positioned relative to the width of the flange 41 so that it will be positioned at 35 the very inner edge of the web 20 as particularly shown in Figs. 4, 7, and 8.

The apron portion 40, see Fig. 2, is preferably bent under the angle bar 27 and secured in position by the rivets extending through the horizontal web 26 of the angle bar 27 and the flange 41 is 40 preferably secured in position by the rivets 43 extending through the web 20. The inner end of the apron portion 40 is preferably as shown in Fig. 2 also provided with a pocket to receive a 45 wire such as the wire 42 of Fig. 7 to be positioned adjacent the inner edge of the horizontal web 26 of the angle bar 27.

Adjacent the rear ends of the end walls 21 and 22 of the channel bar 16, there are provided the 50 leg housings and supports 44 and 45 each of which consists essentially of a vertically extending wall portion 46 having a horizontally extending flange 47 at its upper end and vertically extending flanges 48 which extend inwardly from 55 the main wall member 46. The flange portions 47 of each of these housings 44 and 45 engage the lower face of the flange portion 41, see Fig. 7 and are connected to the web 20 by the bolts 49.

60 Adjacent the round corners 24 and 25 of the channel iron 16, there are provided the caster supporting housings 50 and 51. Each of these housings consists essentially in a rounded wall member 52, a horizontally extending flange 53 at its upper end and two vertically extending flanges 54 at the ends of the rounded wall 52 extending inwardly. The flanges 53 of each of the 65 housings 50 and 51 preferably engage the lower face of the flange 41 and are connected to the 70 web 20 by bolts, such as the bolts 49 shown in Fig. 7.

Adjacent to the inner faces of the wall 46 and 75 rear flanges 48 of the housings 44 and 45, there are secured the caster brackets 55 for the casters or rollers 56. Adjacent the inner faces of the

rear ends of the rounded wall 52, there are secured the caster brackets 57 for the casters 58.

In the interest of an ornamental finish, as indicated in Fig. 4, the upper portion of the fabric 33 is defined from the apron portions 39 and 40 by the beading 59 and a second beading 60 parallel to the beading 59 is provided in the apron 39 preferably below the upper edge of the channel bar 16. The space between the beadings 59 and 60 in the present instance corresponds substantially to the width of the upholstered portion 61 which is disposed on the mattress 18 in single bed formation.

In double bed formation when the extension bed 2 is moved out into the position indicated in 15 Fig. 3, the mattress portion 61 is moved over to rest on the main bed section 1 as indicated in dash and dot lines in Fig. 3.

Preferably to limit the outward movement of the bed section 2 relative to the bed section 1, 20 the angle bar 4 is provided with two angle bar abutments 62 having the vertically extending portions 63 for engagement by the vertically extending portions 64 of the angle iron abutments 65 secured to the lower face of the angle bar 27. 25

It is obvious that various changes and modifications may be made to the details of construction without departing from the general spirit of the invention as set forth in the appended claims.

I claim:

1. The combination with an outer metal bed frame constituting a movable bed section having straight vertically extending end wall portions terminating in vertically extending rounded corner wall portions, of a metal frame constituting a stationary bed section in single bed formation, said inner frame having a straight rear wall shorter than the rear wall of said movable bed section, two straight end walls shorter than the end walls of said movable bed section, a straight front wall parallel to but shorter than the rear wall of said stationary bed section, and inclined wall portions extending from the end walls to the front wall of said stationary bed section and clearing the rounded wall portions of said movable bed section in single bed formation, upwardly extending abutments on the front wall of said stationary bed section adjacent to and inwardly of said inclined wall portions, and downwardly extending abutments on the rear wall of said movable bed section spaced from its end walls to align with the abutments of said stationary bed section to cooperate with one another to define the position of said bed sections in fully extended double bed formation. 50

2. A bed bottom supporting frame comprising a metal frame having a straight rear metal wall member and a second one piece metal wall member comprising two straight end walls, a straight front wall parallel to but shorter than said rear wall, and rounded wall portions extending from said end walls to said front wall, casters adjacent the front corners of said frame, and rounded metal housings extending down from said rounded wall portions and supporting said casters and enclosing said casters from view adjacent the corners of said frame. 60

3. In a bed section for a studio couch, the combination with a metal frame having an angle iron bar forming the rear wall and a one-piece channel iron bar with its flanges extending inwardly and comprising two straight side walls, a straight front wall parallel to but shorter than said rear wall, and rounded wall portions extending from said side walls to the front wall, a 65

coil spring mattress mounted on said frame, said angle iron having a horizontal web connected to the rear ends of the upper flange of said channel bar and its vertical web extending upwardly from the outer edge of said angle iron, and a fabric cover extending across said mattress and down on all sides with its rear portion connected to the horizontal web of said angle iron bar and its side and front portions connected to the lower flange of said channel bar.

4. In a bed section for a studio couch, the combination with a metal frame having an angle iron bar forming the rear wall and a channel iron bar with its flanges extending inwardly and comprising two straight side walls, a straight front wall parallel to but shorter than said rear wall, and rounded wall portions extending from said side walls to the front wall, a coil spring mattress mounted on said frame, said angle iron having a horizontal web connected to the rear ends of the upper flange of said channel bar and its vertical web extending upwardly, a fabric cover extending across said mattress and down on all sides with its rear portion connected to the horizontal web of said angle iron bar and its side and front portions connected to the lower flange of said channel bar, casters adjacent the corners of said frame, and housings supporting said casters and enclosing said casters from view adjacent the corners of said frame, said housings having inwardly extending upper flanges connected to the lower flanges of said channel bars with said fabric cover disposed therebetween.

5. In a bed section for a studio couch, the combination with a metal frame having an angle iron bar forming the rear wall and a one-piece channel iron bar with its flanges extending inwardly and comprising two straight side walls, a straight front wall parallel to but shorter than said rear wall, and rounded wall portions extending from said side walls to the front wall, a coil spring mattress mounted on said frame, said angle iron having a horizontal web connected to the rear ends of the upper flange of said channel bar and its vertical web extending upwardly, a fabric cover extending across said mattress and down on all sides with its rear portion connected to the horizontal web of said angle iron bar and its side and front portions connected to the lower flange of said channel bar, the lower edge along the sides, rear and front portion of said fabric cover folded upon itself into a pocket formation, and a wire in said pocket positioned adjacent the inner edge of the horizontal web of said angle iron bar at the rear and adjacent the inner edge of the lower flange of said channel bar at the front and sides.

6. In a bed section for a studio couch, the combination with a metal frame having an angle iron bar forming the rear wall and a channel iron bar with its flanges extending inwardly and comprising two straight side walls, a straight front wall parallel to but shorter than said rear wall, and rounded wall portions extending from said side walls to the front wall, a coil spring mattress mounted on said frame, said angle iron bar having a horizontal web connected to the rear ends of the upper flange of said channel bar and its vertical web extending upwardly, a fabric cover extending across said mattress and down on all sides with its rear portion connected to the horizontal web of said angle iron bar and its side and front portions connected to the lower flange of said channel bar, the lower edge

along the sides, rear and front portion of said fabric cover folded upon itself into a pocket formation, a wire in said pocket positioned adjacent the inner edge of the lower flange of said channel bar at the sides and rear and adjacent the inner edge of the horizontal web of said angle iron bar, casters adjacent the corners of said frame, and housings supporting said casters and enclosing said casters from view adjacent the corners of said frame, said housings having inwardly extending upper flanges connected to the lower flanges of said channel bar with said fabric cover disposed therebetween and anchoring said wire adjacent the inner edge of the lower flange of said channel bar.

7. In a bed section for a studio couch, the combination with a metal frame having a straight rear metal wall member and a second one-piece channel metal wall member comprising two straight end walls, a straight front wall parallel to but shorter than said rear wall, rounded wall portions extending from said end walls to said front wall, said two end walls, front wall and rounded wall portions being all formed by the web portion of said channel wall member with the end flanges extending inwardly, a mattress secured to and supported on the upper inwardly extending flanges, and a fabric cover extending across said mattress and secured to the lower inwardly extending flanges.

8. In a bed section for a studio couch, the combination with a metal frame having an angle iron bar forming the rear wall and a channel iron bar with its flanges extending inwardly and comprising two straight side walls, a straight front wall parallel to but shorter than said rear wall, and rounded wall portions extending from said side walls to the front wall, a coil spring mattress mounted on said frame, said angle iron having a horizontal web connected to the rear ends of the upper flange of said channel bar and its vertical web extending upwardly from the outer edge of said angle iron, and a fabric cover extending across the upper face of said mattress and down into snug engagement with the outer side faces of the mattress and then into snug engagement with the outer faces and lower faces of said angle iron bar and channel iron bar.

9. In a bed section for a studio couch, the combination with a metal frame having an angle iron bar forming the rear wall and a channel iron bar with its flanges extending inwardly and comprising two straight side walls, a straight front wall parallel to but shorter than said rear wall, and rounded wall portions extending from said side walls to the front wall, a coil spring mattress mounted on said frame, said angle iron having a horizontal web connected to the rear ends of the upper flange of said channel bar and its vertical web extending upwardly from the outer edge of said angle iron, a fabric cover extending across the upper face of said mattress and down into snug engagement with the outer side faces of the mattress and then into snug engagement with the outer faces and lower faces of said angle iron bar and channel iron bar, and means for rigidly reinforcing the inner free edges of said cover adjacent to the inner edges of the lower flanges of said angle iron bar and said channel iron bar.

10. In a bed section for a studio couch, the combination with a metal frame having an angle iron bar forming the rear wall and a channel iron bar with its flanges extending inwardly

- and comprising two straight side walls, a straight front wall parallel to but shorter than said rear wall, and rounded wall portions extending from said side walls to the front wall, a coil spring mattress mounted on said frame, said angle iron having a horizontal web connected to the rear ends of the upper flange of said channel bar and its vertical web extending upwardly from the outer edge of said angle iron, a fabric cover extending across the upper face of said mattress and down into snug engagement with the outer side faces of the mattress and then into snug engagement with the outer faces and lower faces of said angle iron bar and channel iron bar, the inner free edges of said cover being folded upon themselves into pocket formations, and a wire in said pocket formations positioned adjacent the inner edges of the lower flanges of said angle iron bar and said channel iron bar.
11. In a bed section for a studio couch, the combination with a metal frame having an angle iron bar forming the rear wall and a channel iron bar with its flanges extending inwardly and comprising two side walls and a front wall, a coil spring mattress mounted on said frame, said angle iron having a horizontal web connected to the rear ends of the upper flange of said channel bar and its vertical web extending upwardly from the outer edge of said angle iron, and a fabric cover extending across the upper face of said mattress and down into snug engagement with the outer side faces of the mattress and then into snug engagement with the outer faces and lower faces of said angle iron bar and channel iron bar.
12. In a bed section for a studio couch, the combination with a metal frame including a channel iron bar with its flanges extending inwardly and comprising two side walls and a front wall, a mattress supported on the inwardly extending flanges at the upper ends of said bar with the side and front walls of said mattress in alinement with the side and front walls respectively of said bar, and a fabric cover extending across the upper face of said mattress and down into snug engagement with the outer faces of the side and front walls of said mattress, the outer faces of the side and front walls of said bar and the lower faces of said lower inwardly extending flanges.
13. In a bed section for a studio couch, the combination with a metal frame including a channel iron bar with its flanges extending inwardly and comprising two side walls and a front wall, a mattress supported on the inwardly ex-
- tending flanges at the upper ends of said bar with the side and front walls of said mattress in alinement with the side and front walls respectively of said bar, a fabric cover extending across the upper face of said mattress and down into snug engagement with the outer faces of the side and front walls of said mattress, the outer faces of the side and front walls of said bar and the lower faces of said lower inwardly extending flanges, the lower edges along the sides and front portion of said fabric cover folded back upon themselves into pocket formations, and a wire in said formations positioned adjacent the inner edges of the lower flanges of said channel bar at the front and sides.
14. In a bed section for a studio couch, the combination with a metal frame including a channel iron bar with its flanges extending inwardly and comprising two side walls and a front wall, a mattress supported on the inwardly extending flanges at the upper ends of said bar with the side and front walls of said mattress in alinement with the side and front walls respectively of said bar, a fabric cover extending across the upper face of said mattress and down into snug engagement with the outer faces of the side and front walls of said mattress, the outer faces of the side and front walls of said bar and the lower faces of said lower inwardly extending flanges, and means for rigidly reinforcing the inner free edges of said cover adjacent to the inner edges of the lower flanges of said channel iron bar.
15. The combination of a couch, comprising a movable member of a studio bed ensemble, of a metallic frame member formed of a sheet-metal channel positioned to form part of the front and ends of the couch with the marginal flanges of the channel extending inwardly horizontally, said member having an open back adapted to permit movement of the couch into nesting position over an associated cot member, a bar along the back of said frame member, connected to the two end portions of said member, and having a forwardly-extended flange approximately in the plane of the upper flange of said channel-member, a spring-structure supported on the flange of said back-bar and on the top flange of said channel member, a cover over said structure including an upholstering fabric, means securing an edge portion of said fabric to one of the flanges of said channel-member, and means securing another edge portion of said fabric to said back-bar.

JOSEPH MARTIN. 55
